UNITED STATES PATENT OFFICE.

ARTHUR H. PITNEY AND JACOB W. OGDEN, OF STAMFORD, CONNECTICUT, ASSIGNEES,
BY MESNE ASSIGNMENTS, TO PITNEY-BOWES POSTAGE METER COMPANY, OF STAM-
FORD, CONNECTICUT, A CORPORATION OF DELAWARE.

PAPER FEEDING AND CONTROLLING DEVICE FOR PRINTING MECHANISMS.

Original application filed April 5, 1922, Serial No. 549,734. Divided and this application filed April 4, 1923. Serial No. 629,858.

To all whom it may concern:

Be it known that we, ARTHUR H. PITNEY and JACOB W. OGDEN, citizens of the United States, residing at Stamford, in the county of Fairfield and State of Connecticut, have invented certain new and useful Improvements in Paper Feeding and Controlling Devices for Printing Mechanisms; and we hereby declare that the following is a full, clear, and exact description thereof, reference being had to the accompanying drawings, which form part of this specification.

This application is a division of our application for printing and registering mechanism filed April 5, 1922, Ser. No. 549,734 (Case No. 6708).

This invention is a novel improvement in printing mechanism, and comprises a printer, an oscillating impression member adapted to co-act with the printing surface and novel means coacting with said member for feeding a strip of paper past the printing point to receive impressions from the printing die when the machine is in condition for operation.

We will explain the invention with references to the accompanying drawings which illustrate one practical embodiment of the invention, which, however, is capable of changes in form, construction and combinations of parts within the scope of the invention. An understanding of the mechanism shown will enable others to adopt and use the invention for various purposes within the scope of claims, which set forth the essentials of the invention and the novel features of construction and novel combinations of parts for all of which protection is desired.

40 In said drawings:

Fig. 1 is a top plan view of the complete machine.

Fig. 2 is a side elevation of Fig. 1.

Fig. 3 is an enlarged detail sectional view 45 through the paper feeding devices.

Fig. 4 is an enlarged sectional elevation of the printing member operating devices, and the impression member.

50 Fig. 5 is a detail view of the devices for controlling the printing and impression members.

Fig. 6 is a top plan view of the impression member, and shows the printing member and the controlling devices of the printing and impression members in dotted lines. 55

Fig. 7 is a detail view of the paper guide.

Fig. 8 is a detail section on the line 8—8 Fig. 7.

The machine as shown in our aforesaid application and in Figs. 1 and 2 of the drawings comprises a suitable base or support on which is mounted the printing means 2, comprising an adjustable stamp carrier 100 containing a multiple of stamp carrying dies or members P and means whereby any one 60 of such members can be operated when properly positioned at the printing point; (2) means for feeding a strip of paper past the printing point; (3) a meter 200 containing 65 registering mechanism adapted to be 70 operated by the mechanism which operates the stamp and paper feeding devices when the machine is in condition for operation, and to register the money value of the 75 stamps printed by the machine, when the machine is adapted for use as a postage 80 meter, in accordance with the value of the stamp printed, all as more fully explained in our aforesaid application.

The printing means and meter are mounted upon a base plate 103 which is fastened to the top 1 of a suitable hollow supporting member or trough 2 which is mounted upon a suitable floor stand 3 and supports the operative parts at about the height of an 85 ordinary table in convenient position for manipulation by the operator. The meter 200 is also detachably attached to this plate 103 beside the printing mechanism as explained in our aforesaid application. The 90 paper feeding devices are mounted upon the top 1 in proper relation to the printing devices; and the main operating mechanisms and the trip devices controlling the operations of the machine are preferably arranged 95 beneath the plate 1 within the member 2.

In the construction shown in the drawings the printing mechanism comprises a plurality of printers or dies one for each denomination of stamp used in the machine 100 mounted on a rotatable support. In the example shown there are 5 such printers (see

Fig. 1) which are adapted to print stamps of the amounts 1¢, 2¢, 3¢, 5¢ and 10¢. These stamps are mounted on vertical spindles 112 journaled in a rotatable member 100 which 5 may be conveniently formed of suitable castings, as fully explained in our aforesaid application.

Each die or printed member is provided with inking means 118 which may be of any 10 suitable kind, but are preferably constructed as explained in our aforesaid application.

To bring any printer P to printing position, the head 100 is turned until a clutch member 112^a of the desired printer registers with the clutch member 108, as indicated 15 in Fig. 3 and then it can be operated by power transmitted to such member 108, as described in our aforesaid application.

20 *The impression devices.*

Suitably, located to produce impressions from the die P that is adjusted to printing position is an impression member adapted 25 to cooperate with the printer in making impressions when paper or mail matter, etc., is passed there-between.

As shown this impression member comprises a sector 4 (Figs. 1, 2, 4 and 6), which 30 is provided with a recess in its outer face in which is secured a preferably rubber faced block 4^a, whose rubber face 4^b is molded to conform to the circumference of the sector 4 and provides the resiliency necessary 35 for producing a clear impression from the printing surface on the printer.

Projecting rearwardly from sector 4, is 40 a shorter sector arm 4^c, having an arc shaped slot through which extends a friction member (described later) designed to prevent sector 4 moving too freely on the shaft 8. Securely fastened to the top and bottom of 45 sector 4 (see Figs. 3 and 6), are two similarly formed plates 4^d, whose outer ends extend beyond the circumference of the sector 4 and afford a support and bearing for the paper feed clamp 5.

Loosely pivoted on the shaft 8 between 50 the upper and lower sections of the sector 4 is an arm 14 (Figs. 3, 19 and 25) to the outer end of which are fastened two flat segmental plates 15, which are situated one over and one under the sector 4, which can move freely between them. A distance 55 piece 16 is interposed between and fastened to the plates 15, and passes freely through a curved slot in sector 4. Each plate 15 has a curved tongue 15^b on its inner face, which engages corresponding slots 4^e in the top 60 and bottom of the sector 4 and acts as guides for the travel of plates 15. Each plate 15 has a lip 15^a, (Fig. 4) on its outer edge projecting toward each other, and the radius of the inside surface of each lip 15^a

is very slightly greater than the radius of 65 the sector 4. A clamp 17 shaped like a pawl is pivoted to each plate 15 and pressed against the inner side of the lip 15^a by a spring 17^a. The stops 18 and 19 located on the shelf 70 limit the travel of the arm 14. 70

Sector 4 is loosely mounted on a vertical shaft 8 which is supported by and has its bearing in a bracket 9 which is preferably adjustably fastened to the table 1, to enable the impression member to be adjusted 75 toward or from the printer to regulate the impression pressure. The shaft 8 extends through the table 1 and on the lower end of shaft 8 is fastened a lever arm 10 (see Fig. 6) and at the upper end of shaft 8 80 is also fastened by key and set screw a lever arm 6 which straddles the sector 4 at the shaft. At the outer end of the arm 6, are pivoted two links 7 (Figs. 1, 3 and 6), one above and one below the sector 4 which 85 links lie in the same plane as the plates 4^d of the sector 4. The outer ends of these links 7, are pivoted to the heel of the clamp 5, in such a way that any motion of the lever 6 relative to sector 5 will cause the 90 clamp 5 to rock on its bearings in the plates 4^d.

The arm 14, has a rearwardly extending sector 14^a which is slotted like the arm 4^c, and for the same purposes, both of them engage the same friction member.

This friction member consists of a sleeve 25 (Figs. 3 and 4) loosely mounted on a stud 24 which is secured to the bracket 9. The sleeve 25 is flanged near its bottom end, and the top end is threaded for the tension adjustment nut 29, and that part of it below the flange is slotted to engage a pin 24^a, on stud 24 (Fig. 4) which prevents sleeve 25 from turning on the stud 24 when the nut 29 is turned. Both stud 24 and its sleeve 25 pass clear through the curved slots in the arms 4^c and 14^a. Friction disks 26, of cork or leather, are placed on the sleeve 25, one between the flange on sleeve 25, and the arm 110 4^c, one between the arm 4^c and 14^a and one on top of arm 14^a between it and a steel disk 27. A spring 28 is interposed between the disk 27 and the nut 29 and forces the friction disks to bear on the faces of 115 both the arms 4^c and 14^a, giving the desired friction. The nut 29 makes it possible to vary the amount of resistance as required.

The machine shown in an aforesaid application is adapted to print stamps upon 120 a strip of suitable material, preferably gummed paper. As shown (Figs. 1 and 6), a strip of paper S is led from a roll 20 loosely mounted on a stud 21 on cover plate 70 to and between two parallel guide plates 125 22 mounted on the said cover plate, and then led around the curved surface of the printer sector 4 and between such surface and the

guide flanges 15^a on the plates 15. The strip S is wide enough to fill the space between the plates 15 so that its edges are held by clamps 17 against the inner face of the flanges 15^a (Fig. 4) while the body of the strip covers the face of the platen 4^b of the sector 4.

The plates 22 are formed with registering openings 22⁰ (Figs. 7 and 8), through which 10 the head 23^a of a detector lever 23 could project if not prevented by the pressure of the strip of paper S. The strip of paper between the plates normally holds the member 23 in the position shown in Fig. 1. 15 This member 23 is attached to the upper end of rod 55. The head of lever 23 presses slightly against the strip S and acts as a drag or brake thereon which prevents the accumulation of slack in the strip between the plates 22 and the impression 20 member or printing point.

On the lower end of shaft 8 (Fig. 6) directly below the lever arm 10, is loosely pivoted a lever arm 11 to the outer end of 25 which arm is attached the link 12, which at its other end engages with the race cam 13. (Figs. 4 and 6.) The cam revolving in the direction of the arrow imparts a reciprocating motion to the arm 11. The 30 arm 11 has a projection 11^a on its end, adapted to engage the arm 10 and communicates its motion to it, when moved in the direction of the arrow. A spring 10^a is connected to the arm 10 to effect its return with the arm 11 as described in our 35 aforesaid application.

The cam 13 is suitably geared to the drive of the printer and revolves in the same direction and at the same speed as the printer. The arms 10 and 6 on the shaft 8, 40 being fast thereto, any movement of arm 10 will be communicated through shaft 8 to arm 6 as described in our aforesaid application. The parts herein are numbered correspondingly to parts in our aforesaid 45 application and we refer thereto for a full explanation and illustration of parts mentioned herein but not forming part of the present invention.

50 In printing a stamp the die makes one complete revolution and with it the cam 13. The rollers 12^c (Fig. 6) prevent the link 12 from moving laterally, so that the pin 12^a and roller 12^b on the link 12 riding in the slot 13^b of the revolving cam 13 forces link 12 to move in the direction of the arrow pulling the arms 11, and 10 with it. Arm 6 in moving pushes the links 7 and rocks the clamp 5 in towards the circumference of the impression member or sector 4 which is preferably slightly nicked to engage the clamp. Sector 4 because of the friction applied to the arm 4^c, remains at rest while the aforesaid movements of parts 6, 7 and 5 take place. The gummed

paper strip S lying between the clamps and the surface of the sector 4 is caught and clamped tightly there between.

Continuing its forward motion the arm 6, (through the pressure it exerts on the clamp 5) carries both sector 4 and strip S with it, and the strip S slips forward past the clamps 17 and the die makes an imprint on the part of the strip S which lies opposite the rubber cushion 4^b. Before the sector 4 has completed its forward travel the end of the curved slot 4^c therein engages the distance piece 16 of the plates 15 and carries them forward to the end of the stroke; at which time the arm 14 rests 80 against the stop 18. After the printing surface of the printer P has cleared the sector 4, and while it is completing one revolution, the plates 5 and sector 4 are returned to first position.

At the beginning of the return movement the sector 4 is held stationary by the friction member, and the arm 6 with the links 7 move back; the clamp 5 is first rocked out of engagement with the sector 4 and releases its hold on the strip S, which is held by clamps 17. A hook 7^a of the upper link 7 then engages a detent in the plate 4^d and pulls said plate and the sector 4 back to the starting positions. On this return movement, the other end of slot 4^c in sector 4 engages the distance piece 16 and returns the plates 15 to their original first position also.

On the return movement of the plates 15, the part of the strip S, which is clamped to them by clamps 17, is moved back also. This backing up of the strip S shortens the blank space between the several impressions, and for this purpose the arm 14 and plates 15 are used. The contour of the cam slot 13^b of cam 13 is such as to advance the impression or sector 4 slowly, to near the point at which it engages the die, and from that point till a little after the engagement 110 ends, the surface speed of the impression member or sector 4 is equal to the surface speed of the die. When this point is passed the remainder of the time of revolution is used to return the parts to their original 115 position, the travel of the roller 12^b of link 12 in making the steep descent in the cam slot 13^b is assisted by the pull of the spring 10^a.

The printing surface of the die P will 120 not interfere with the clamp 5 because it is moved out of the way at the time the die passes the point of contact with the sector. Clearance over and under the die is provided for the projecting parts 4^d and 7.

125 Any suitable devices may be used for severing the printed stamp from the strip. As shown (Figs. 3 and 6) a pair of shears 31 and 32 is mounted on and between the guide plates 15 to cut the printed tapes as de-

sired. The fixed blade 31 is fastened to a block 30 rigidly secured to and between the plates 15. The movable blade 32 is hinged to block 30, and its upper end passes through 5 a slot in plate 35, which is fastened on top of the upper plate 15. A back guide 33 is also fastened to block 30, and a front guide 34 is fastened to plate 35 to guide the tape between the blades of the shears, the cutting 10 being effected by the operator moving the protruding end of the hinged blade 32 with his fingers.

As the last stamp printed on the strip lies between the shears and sector 4, it is 15 necessary to rock the sector 4 by hand without printing another stamp, in order to feed the strip forward and to move the last imprint to the outside of the shears. To accomplish this a knurled knob 36 is securely 20 fastened to the top end of the shaft 8 (Figs. 1, 2, 4) and by turning this knob all the strip feeding operations above described as having been performed automatically by 25 the driving action of the cam 13, can be performed without moving the printer, and consequently without putting an imprint on 30 the strip. This is because the lever 10 is free to move (in the direction of the arrow in Fig. 6) independently of the power derived from the positively driven lever 11.

In order to prevent an impression being made if there is no strip between the printing die and impression member, the lever 23 which acts as a drag on the movements of 35 the tape between the guide plates 22, is connected with suitable tripping mechanism below the table 1. The gummed strip S is usually fastened to the spool, and a rectangular hole Fig. 7 is punched through the 40 tape a proper distance from its inner end and when this punched part of the strip passes between the plates 22 the head of lever 23 will be able to project through the 45 hole in the strip, and in so doing, it actuates devices which automatically renders the printing inoperative as described in our aforesaid application when applied to the machine shown therein. The hole in the 50 tape should be made long enough to allow the completion of the printing of a stamp on a preceding part of the strip in the event the lever 23 projects through such hole at the beginning or during the course of a 55 printing operation.

The printer may be of any suitable kind and operated by any suitable means to contact with the impression number; and said member may be operated by any suitable means to cooperate with the printer, as described.

In the drawings the printer and impression member are illustrated in connection with the machine shown in our aforesaid application. As shown therein the main 65 shaft from which the motive power is trans-

mitted to all operative parts of the machine is the shaft 39 indicated in Fig. 6 which is driven, from a horizontal drive shaft 40 by bevel gears 41 and 42. The shaft 39 through a suitable clutch 44 transmits motion to the shaft 104 from which motion is transmitted to the die spindle 112, impression sector P, and the meter. The trip mechanism indicated in Fig. 6 acts directly on the clutch, making or breaking its connection with the shaft 39 and, with the exception of the original impulse given it to start a printing operation, it works automatically.

On the hub of the clutch 44 is a spur gear 71 which through the suitable gears drives the cam 13 as indicated in Figs. 4, 5, and 6. The tail of the clutch cage is adapted to be engaged by the arm 46^a of the stop lever 46 and the clutch body has a cam flange 44^c adapted to be engaged by a roller on the arm 46^b of lever 46 and return it to its original position. The lever 46 can be oscillated on its stud 46^a. A link 48 connects arm 46^c of lever 46 with a rocking arm 49, which is connected with a rod (not shown) which extends horizontally through the base of the printing member and protrudes through and into the back wall of the meter. This rod is continually urged by a spring in the direction of the meter, so that its end when permitted will be pushed into the body of the meter, but its entry or non-entry thereinto is controlled by the shutter lever of the meter as described in our aforesaid application.

A lever 51 with two arms 51^a and 51^b is mounted to oscillate on a stud 51^a (Fig. 4) under the influence of a spring 51^c and the link 51; a stud 52 limiting the movement of 51 under the pull of spring 51^c. A link 53 transmits the motion of the trip lever arm 54 to the lever 51. The spring 53^a holds the hook end of the link 53 in contact with the trip arm 54. A lever 54 with two arms 54^b and 54^c can be oscillated on its stud 54^a under the influence of the hand operated push button 64, located on an exposed part of the machine (Fig. 1) and is returned to place by the cam 13. A vertical spindle 55 is mounted in the machine as shown in (Figs. 6 and 8) and upon the upper end of spindle 55 is securely fastened the drag 23 on the tape 20, Fig. 1. This spindle extends downward through the table to a position above the level of the cam 13; at this point another lever 56 is fastened to oscillate with the upper lever 23.

A rod 57 is pinned to the free end of the lever 56 and extends forward over cam 13, on the level of the link 53 and projects through a hole in the block 62, nearly touching link 53 when both are in their normal positions (i. e. when the trip is at rest and the lever 23 is resting on the tape S). 130

But when no tape is between the plates 22, or what is the same thing, when the hole in the tape is in line with the hole in the plates 22 and allowing lever 23 to project 5 through the hole, the rod 57 is pushed forward by power of the spring 23^a, which is strong enough to overcome the pressure of spring 53^a, and pushes link 53 out, so that its hook cannot engage with the trip 10 lever 54.

A lever 58, (Fig. 6) is normally in position to prevent the oscillation of the stop lever 46, spring 58^a furnishing the necessary motive power. 58^b is a limiting stop 15 for the travel of the lever 58. The lever 51 under pressure of its spring 51^a is always normally positioned so as to prevent the oscillation of stop lever 46.

A guide 63 is provided for the free end 20 of the link 53, and the cam shaped end 53 engaging the guide will be forced out of engagement with the lever 54 at the proper time. If the spring 50^a (not shown) tending 25 to oscillate the clutch stop lever 46, is prevented from acting the stop 46 cannot move and the clutch can not be operated. All the aforesaid parts for actuating the printer and the impression member and 30 controlling the operation thereof are more fully described and shown in our aforesaid application similar parts therein being similarly numbered; and as the particular constructions of said parts (or of any specific actuating means for the printer and 35 the impression member) is not claimed herein, further explanation and illustration thereof is unnecessary.

What we claim is:

1. In combination, a printer, a coacting 40 impression means comprising an oscillating member having an impression surface adapted to coact with the printing surface, a rocking lever, a paper clamp mounted on the member, means whereby on one motion 45 of the said lever the clamp is caused to engage the paper and the member moved in a direction to feed the paper, and on the reverse movement of the lever the clamp is caused to disengage the paper and the members moved back, substantially as described.

2. In combination with mechanism as set forth in claim 1, a paper guide loosely mounted below the member, a paper clamping device carried by said guide and means 55 whereby the guide is given a limited movement with the member near the ends of both strokes thereof.

3. In combination with mechanism as set forth in claim 1, frictional devices whereby 60 the movable member is arrested until positively actuated by the movement of the lever.

4. In combination with mechanism as set forth in claim 1, a pair of paper guide plates above and below the member, paper

clamping devices carried by said plates, means whereby the plates are given a limited movement with the member near the ends of both strokes thereof, and stops for limiting the movement of said plates. 70

5. In combination, a printer, a coacting impression means comprising an oscillating sector having an impression surface, a lever pivoted concentric with the sector, a paper clamp pivotally mounted on the sector, a link connecting said lever with said clamp, and means whereby on one motion of the said lever the clamp is caused to first engage the paper and the sector moved in the direction to feed the paper, and on the reverse 80 movement of the lever the clamp is caused to first disengage the paper and then the sector moved back, and devices whereby the sector is arrested until actuated by the movement of the lever, substantially as described. 85

6. In combination with mechanism as set forth in claim 5, a guide plate loosely mounted below the sector, a paper clamp carried by said plate, and means whereby the plate is given a limited movement with 90 the sector near the ends of both strokes thereof, substantially as described.

7. In combination with mechanism as set forth in claim 5, segmental plates pivoted above and below the sector, and having 95 guide flanges on their outer peripheries, and paper clamping devices on said plates adapted to coact with the flanges of the plates to hold the paper.

8. In combination a printer; a rock shaft, a sector loosely pivoted on said shaft and adapted to coact with the printer, a lever fixed on said shaft, a clamp pivotally mounted on the sector, links operatively connecting the said lever with said clamp whereby 100 on one motion of the said lever the clamp is caused to first engage the paper and then the sector moved in the direction to feed the paper, and on the reverse movement of the lever the clamp is caused to first disengage 110 the paper and then the sector moved back, and devices whereby the movement of the sector is arrested until it is actuated by the movement of the lever.

9. In mechanism as set forth in claim 8, 115 a pair of paper guide plates loosely mounted on the shaft above and below the sector, paper clamping devices carried by said plates and means whereby the plates are given a limited movement with the segment 120 near the ends of both strokes thereof.

10. In combination a printing member; paper feeding and impression means cooperating therewith comprising a sector having an impression surface, and a rock shaft 125 and connections for operating said impression means, with means whereby said shaft may be positively rocked in one direction to feed the paper during the printing operation; and means whereby the shaft may be 130

manually rocked to move the sector in the direction to feed the paper without producing an impression thereon.

11. In combination with mechanism as set forth in claim 10, means for directing a strip of paper to and between the impression member and printer, means for detecting a hole or break in the paper in the strip and means controlled by the detector whereby printing is prevented when the hole or break is detected.

12. In combination a printing member; a paper feeding and impression member cooperating therewith, comprising a sector having an impression surface, a rock shaft carrying said sector, means connected with the sector for clamping the paper, with mechanism whereby said shaft may be positively rocked in one direction to feed the paper during the printing operation, and means whereby the shaft may be manually rocked to move the sector in the direction to feed the paper after a printing operation and when the printer is locked.

13. In combination with mechanism as set forth in claim 12, means for directing a strip of paper to and between the impression member and printer, means for detecting a hole or break in the paper in the strip and means controlled by the detector whereby printing is prevented when the hole or break is detected.

14. In combination a printing member; an impression member cooperating therewith, a clamp carried by said member, paper guiding plates on said member, an arm carrying said plates, a rock shaft, a rocking lever on said shaft, links operatively connecting said lever with the member, and means for permitting the member to move a predetermined extent in either direction and then cause the plates to move therewith a short distance.

15. In combination with mechanism as set forth in claim 14, means whereby said shaft may be positively rocked in one direction to feed the paper during the printing operation, and means whereby the shaft may be manually rocked to move the sector in the direction to feed the paper after a printing operation and when the printer is locked.

16. In combination with mechanism as set forth in claim 14 means for directing a strip of paper to and between the impression member and printer, means for detecting a hole or break in the paper in the strip and means controlled by the detector whereby printing is prevented when the hole or break is detected.

17. In combination a printing member; and paper feeding and impression means cooperating therewith, comprising a sector having an impression surface, a cam member carried by said sector, paper guiding plates above and below the sector, an arm

carrying said plates, means connected with the plates for clamping the paper, a rock shaft, a lever fixed on said shaft, links operatively connecting said lever with the sector and means for permitting the sector to move a predetermined extent in either direction and then cause the plates to move therewith a short distance.

18. In combination with mechanism as set forth in claim 17 means whereby said shaft may be positively rocked in one direction to feed the paper during the printing operation, and means whereby the shaft may be manually rocked to move the sector in the direction to feed the paper after a printing operation and when the printer is locked.

19. In mechanism of the character specified the combination of a printer and means for actuating the same; a sector having an impression surface adapted to cooperate with the printer, a paper clamp pivotally mounted on said sector adjacent the impression surface, a rock shaft, a lever attached to said shaft, links connecting said lever with the said clamp whereby it is opened and closed by the lever and the sector is caused to move with the lever after the clamp is opened or closed; an arm loosely mounted on said shaft, a paper guide plate connected to said arm; a paper clamp carried by said guide plate adapted to prevent backward movement of the strip of paper when the main clamp is released, and means whereby the plates are caused to move with the segment only near the ends of its stroke.

20. In combination with a mechanism as set forth in claim 19 means for frictionally yieldingly retarding the movement of the sector and of the arms carrying the plates.

21. In mechanism as set forth in claim 19 the sector having an extension provided with a segmental slot and the arm having an extension provided with a segmental slot, a member extending through the slots in the said extension, and frictional devices on said member engaging the said extension to retard the oscillatory movements of the sector and the said plates, substantially as described.

22. In mechanism of the character specified the combination of a printer and means for actuating the same; a sector having an impression surface adapted to cooperate with the printer, a paper clamp pivotally mounted on said sector adjacent its impression surface; a rock shaft, a lever attached to said shaft, links connecting said lever with the clamp on the sector, an arm loosely mounted on said shaft, plates connected by said arm above and below the sector, paper clamps carried by said plates adapted to prevent backward movement of the strip of paper when the main clamp is released; and a member connecting said

- plates and extending through a slot in the sector whereby the plates are caused to move with the sector only near the ends of its strokes.
- 5 23. In combination with a mechanism as set forth in claim 22 means for frictionally yieldingly retarding the movements of the sector and of the arm carrying the plates.
24. In mechanism as set forth in claim 22, 10 the sector having an extension provided with a segmental slot and the arm having an extension provided with a segmental slot, and a member extending through the slots in the said extensions and frictionally engaging the same to retard the oscillatory movements of the sector and the said plates, substantially as described.
25. In a machine of the character specified; a plurality of printers for printing 20 stamps of different denominations; means whereby any printer may be brought to the printing point, an impression member adjacent the printing point and means for taking an impression from the printer at the 25 printing point, with means for directing a strip of paper to and between the impression member and printer, means for detecting a hole or break in the paper strip, and means controlled by the detector whereby printing 30 is prevented when a hole or break is detected.
26. In combination with mechanism as set forth in claim 1, a detector engaging the paper and normally held in effective posi-
- tion by contact with the paper, and means controlled by the detector whereby when the detector finds a hole or break in the paper further printing is prevented, substantially as described.
27. In combination with mechanism as set forth in claim 5, means for rendering the impression means ineffective; a detector adapted to engage the paper and be held thereby in ineffective position, and means connected with the detector for yieldingly holding it in contact with the paper and whereby the detector is operated when it finds a hole or break in the paper and releases the mechanism whereby further printing is prevented.
28. In combination with mechanism as set forth in claim 8, means for rendering the impression means ineffective, means for guiding the strip, comprising a guide plate provided with an opening, a detector adjacent the plate having a tooth adapted to engage the strip and be held thereby out of the opening in the plate, and means connected with the detector for yieldingly holding it in contact with the strip and whereby the detector is operated when it finds a hole or break in the strip to trip the mechanism whereby further printing is prevented.

In testimony that we claim the foregoing as our own, we affix our signatures.

ARTHUR H. PITNEY.
JACOB W. OGDEN.
